UNITED STATES PATENT OFFICE

2,449,688

DEHYDRATOR FOR REFRIGERATING SYSTEMS

Clinton C. Brinkoeter, San Antonio, Tex., assignor to Ed Friedrich, Inc., San Antonio, Tex., a corporation of Texas

Application November 27, 1944, Serial No. 565,396

8 Claims. (Cl. 62—115)

1

My invention is a unit which is designed to remove the moisture, commonly found in liquid refrigerant in refrigeration installations, which causes considerable trouble in the sticking of expansion valves and corrosion with some refrigerants.

Primarily, my invention seeks to provide a unit which may be connected in the refrigerant circuit of a refrigerator for a sufficient time to dehydrate the refrigerant, and may then be disconnected and, after removal of the condensate water, may then be connected in the circuit of another refrigerator to effect dehydration of the refrigerant therein or re-connected to the first refrigeration circuit.

Another object is to provide a dehydrating unit of a simple, comparatively inexpensive nature which can be easily installed in and disconnected from the refrigerant circuit of a refrigeration system.

Other objects will in part be obvious and in part be pointed out hereinafter.

To the attainment of the aforesaid objects and ends the invention further resides in the novel details of construction, combination and arrangement of parts, all of which shall hereinafter be described and then be specifically pointed out in the appended claims, reference being had to the accompanying drawings in which:

Fig. 1 is a part central vertical longitudinal section and part side elevation of the dehydrator.

Fig. 2 is a central vertical longitudinal section of the same.

Fig. 3 is a horizontal section on the line 3—3 of Fig. 1.

Fig. 4 is a detail horizontal section on the line 4—4 of Fig. 2.

Fig. 5 is a diagram showing how the dehydrator is connected in a refrigerating system.

Fig. 6 is a diagrammatic view with the dehydrator in its inoperative position, and showing another way of connecting the dehydrator to the refrigerating system.

In the drawings, in which like numerals and letters of reference indicate like parts in all the figures, 1 represents the outer shell of the case or cabinet in which the operating parts are located. An inner shell 2 is spaced from the outer shell by two walls of suitable insulation 7 between which an intermediate shell 5 is located. An inner bottom plate 3 and an outer bottom plate 4 have insulation 7, separated by an intermediate plate 6.

The upper end of the inner shell 2 is connected with the outer shell 1 by a cover 8 over the insu-

2

lation 7. The outer shell 1 extends above the cover 8 for some distance to provide an upper chamber UC, while the inner shell 2, bottom plate 3 and cover 8 enclose a lower chamber LC. The chamber UC is closed by a cover consisting of a sheet 11 of metal or other suitable material carried by an angle ring 10 which fits into the angle ring 9 to which the shell 1 is suitably attached.

Coupling members 12, 13 and 14 are secured to the shell 1 in any suitable way. The coupling members 12 and 13 are adapted to be connected in the line between the compressor and the evaporator of the refrigerator so the wet liquid from the compressor will pass into the dehydrator unit 15 where it is dried and then passed as a dry liquid to the evaporator; to the coupling 14 is connected a nipple 43 and a duct 44 having a back-check (one-way opening) valve 46 of any suitable construction, the duct 44 running to the intake side 20 of a snap action two temperature valve 45 of well known construction, the outlet side of the valve 45 being connectable through a nipple 47 to the suction side of the compressor of the refrigerator. The valve 45 also has an inlet port 52 to which a connection from the evaporator is adapted to be made.

A pipe or duct 16 has its inlet end welded as at w to the coupling 12 while its outlet end discharges into the outer coil 15^x of a heat interchanger at or near one closed end 31 thereof (see Fig. 3), the other end of the coil 15^x is connected to an elbow fitting 30 that is screwed into the cover 18.

A T fitting 25 is also threaded into the cover 35 18 of the water separation unit of the dehydrator. The intake end of the inner coil 15 of the heat interchanger is connected to the T fitting 25, as shown in Fig. 2, while the outlet end of the coil 15 is connected to the coupling member 13.

The water separation unit comprises a vessel 17 having its lower end closed and its upper end fitted hermetically about the cover 18. A drain pipe 19 is provided, closed normally by a plug 20, through which the contents of the vessel 17 may be withdrawn when desired.

Within the vessel 17 is located the filter and freezing coil of my apparatus. The filter comprises an outer shell 21 and an inner shell 22 spaced apart, the space between the shells 21 and 50 22 being closed at the ends while the shell 22 is open at the top and communicates with the space between the shell 21 and the wall of the vessel 17 as best shown in Fig. 2. Surrounding the shell 22 and spaced therefrom is a screen 24 and a filter 23 of any approved construction. A duct 26 is se-

cured at its upper end to the intake branch of the T fitting 25 and passes through the shell 22 and communicates with the space inside the screen 24. A drain pipe 27 connected to the shell 21 at its bottom passes through the insulated bottom of the case and is normally closed by a plug 28.

The freezing coil 29 has its upper end connected to the elbow fitting 30 and its lower end to the drain 27 adjacent the bottom of the shell 21 and encircles that shell and a cup 35 that is mounted above the shell 21 and spaced therefrom. The shell 21 has radial spacers 51 for the coil 29.

A nipple 32 is screwed into the cover 18 and communicates with a short suction pipe 34 that projects into the cup 35 and is spaced from the bottom thereof a suitable distance. A pipe 33 connects the nipple 32 to the coupling member 14.

The cup 35 has an opening in its bottom, surrounded by a stand pipe 36, and a center tube 37 of less height than the stand pipe to form a back stop for the float valve proper 38^a of the case 38 of the valve unit. The case 38 is threaded through the cover 18 and projects into but is spaced from the stand pipe 36 and has a seat 39 for the float valve 38^a. The case 38 also has its passage provided with a regulating and shut-off valve 41 (over which is a cap 42) and valve seat 40. The case 38 has a nipple 49 to which is coupled one end of a pipe 50 that leads from the third leg of the T 25.

The vessel 17 and shell 22 are filled to a predetermined liquid line with refrigerant 48 in which the larger part of the coil 29 and the bottom of the cup 35 are immersed.

An amount of refrigerant is placed in the coil compartment of the water separation unit so that when the apparatus is connected up to the refrigerator system the temperature of the coil compartment can be brought down to 10° to 15° before valve 41 is opened to let in additional liquid.

The application of my invention to a refrigerating system is shown in Fig. 5 of the drawing, by reference to which it will be seen that the suction line 55 from the evaporator E to the compressor COM is cut and the ends are connected respectively to the nipple 47 and to port 52 of the valve mechanism 45.

The outlet from the reservoir RES is connected by a duct 53 to the coupling member 12. The outlet coupling 13 is connected by a duct 54 to the expansion valve EV, which is in turn connected to the inlet side of the evaporator E by a duct 56. The compressor COM delivers the refrigerant via duct 57 to the condenser CON. From the condenser the refrigerant passes, via duct 58, to the reservoir RES. The motor control system 59 is set to keep (in cooperation with valve 45) the temperature in the dehydrator at about 5°.

Assume the dehydrator to be connected in a refrigeration system as indicated in Fig. 5 and that the system is in operation. Refrigerant will flow from the compressor COM via duct 57 through condenser CON, via duct 58 into reservoir RES. From reservoir RES refrigerant will flow via duct 53, to coupling member 12 and into the heat interchanger via pipe 16. The refrigerant will enter the outer coil 15^x of the heat interchanger adjacent its closed inlet end 31 (Fig. 3) and flow through that coil in the space between the coils 15^x and 15 to the other closed or outlet end of the coil where it passes into the elbow fitting 30. From elbow fitting 30 the refrigerant liquid passes into the upper end of the

freezing coil 29, the lower end of which delivers the liquid into the pipe 27 from which it passes into the shell 21. The liquid in the shell 21 passes through the filter 23 and the strainer 24 to the duct 26 and via the duct 26 to the T-fitting 25.

A regulated portion of the liquid passes from the T-fitting 25, via pipe 50, nipple 49, valve 41, case 38, valve 38^a, stand pipe 37 into vessel 17 to cover a substantial portion of the coil 29. Float valve 38^a is so constructed as to let the liquid pass into pipe 37 until a predetermined level within vessel 17 is reached whereupon valve 38^a closes on seat 39.

The main portion of the refrigerant passes from the nipple 25 into the entrant end of coil 15 and through that coil to coupling member 13. From coupling member 13 the liquid passes, via duct 54, through expansion valve EV to duct 56 of the evaporator E and from the evaporator it passes via duct 55 and the snap action two-temperature valve 45 back to the compressor.

A suction is created (under control of valve 45) in the upper part of the vessel 17 through the connection 34, 33, 43, 44, 46 to valve 45. This causes evaporation of liquid in vessel 17 and serves to maintain the temperature in vessel 17 at from 10° to 15° F. The fluid sucked from vessel 17, via valve 45, is returned to the compressor via duct 55. In this way any moisture that is in the wet liquid is frozen before arriving at the filter and strainer and is prevented from entering the line to the refrigerator or to the float valve. After the unit has been left on operation from forty-eight to seventy-two hours the liquid will have passed through the unit several times and all moisture will have been left in the strainer compartment 21 in a frozen state. After the unit is removed from the installation, ice in vessel 21 will thaw and the water can be drained through outlet 19.

Another way in which the dehydrator may be used to advantage as a service device to effect dehydration of a refrigerating system, the connections being such that the dehydrator can be connected and disconnected readily without stopping the operation of the refrigerating system, is shown in Fig. 6. To that end I may provide two-way valves 59, 63 and 64. In Fig. 6 is shown the connection between the compressor COM and the evaporator E. The connection includes the duct 55^x and one, 63, of the valves, a branch 55^x connecting the valve 63 with the valve 45 at 47. Also the duct 60 between the reservoir RES and the expansion valve EV includes the valves 64 and 59, there being a branch 61 between the coupling 13 and valve 59 and a branch 62 between the valve 64 and the coupling 12.

With the valves 59, 63, 64 set as shown in Fig. 6, the dehydrator is operatively disconnected. In order physically to disconnect the dehydrator one needs only to uncouple ducts 61 and 62 from the couplings 13 and 12 respectively, and uncouple duct 55^x from valve 45.

To physically remove the dehydrator from the system with the arrangement shown in Fig. 5, pipes 53 and 54 are disconnected and then coupled together and pipes 55 are disconnected from valve 45 and coupled together, if the refrigerator is to be run without the dehydrator.

However, by using the arrangement shown in Fig. 6 with the valves 59, 63 and 64, when the valves are positioned as shown one simply disconnects pipes 61, 62 and 55^x from the valves 59, 64 and 63 respectively. The dehydrator may

then be similarly connected in another refrigerator circuit, and so on for dehydrating a number of refrigerator fluids with the one dehydrator.

With the parts connected as shown in Fig. 6 to render the dehydrator operative, one need only turn valves 59, 64, 63 90° in the direction of the arrows, thus connecting ducts 60, 61 via valve 59, ducts 62, 60 via valve 64 and ducts 55, 55* via valve 63. Duct 60* will then be closed at both ends.

After the dehydration has been completed, valves 57, 58 and 59 are restored to the position of Fig. 6, whereupon the dehydrator may be disconnected and transferred to another installation without interfering with the continuous operation of the refrigerating system.

Any oil which may be trapped in the vessel 17 and the water from melted ice that forms in vessel 21 may be removed, when the dehydrator is inoperative, through drain pipes 19 and 27 respectively.

From the foregoing description, taken in connection with the accompanying drawings, it is thought that the construction, operation and advantages of the invention will be clear to those skilled in the art.

What I claim is:

1. A dehydrator for refrigerating systems containing a refrigerant in a refrigerating circuit, said dehydrator including: a casing; a water separation unit in said casing; a heat interchanger in said casing; operative connections between said heat interchanger and said water separation unit, by virtue of which the refrigerant to be dehydrated is first passed through one part of said heat interchanger, then through said water separation unit, and then through another part of said heat interchanger; and means whereby said heat interchanger may have its terminals operatively connected in the refrigerant circuit of the refrigerating system.

2. A dehydrator for refrigerating systems containing a refrigerant in a refrigerating circuit, said dehydrator including: a casing; a water separation unit in said casing, said water separation unit including a shell, a filter unit within the shell, a freezing coil surrounding said filter unit and in circuit with a heat interchanger located in said casing; operative connections between said heat interchanger and said water separation unit, by virtue of which the refrigerant to be dehydrated is first passed through one part of said heat interchanger, then through said water separation unit, and then through another part of said heat interchanger; and means whereby said heat interchanger may have its terminals operatively connected in the refrigerant circuit of the refrigerating system.

3. A dehydrator for refrigerating systems containing a refrigerant in a refrigerating circuit, said dehydrator including: a casing; a water separation unit in said casing; a heat interchanger in said casing; operative connections between said heat interchanger and said water separation unit, by virtue of which the refrigerant to be dehydrated is first passed through one part of said heat interchanger, then through said water separation unit, and then through another part of said heat interchanger; and means whereby said heat interchanger may have its terminals operatively connected in the refrigerant circuit of the refrigerating system, said water separation unit including a shell, a filter unit within the shell, a freezing coil surrounding said filter unit and in circuit with said interchanger, and means

for lowering the temperature in said shell below freezing, said last named means including a cup mounted within said shell, means for delivering refrigerant to be dehydrated into said cup.

5 4. A dehydrator, including a closed casing having its bottom and its side wall for a predetermined height heat-insulated, and enclosing a chamber, a portion of which is surrounded by said side wall heat insulation; a water separating unit including a vessel located within the insulated part of said chamber, liquid-filtering and water-freezing instrumentalities in said vessel; a heat interchanger located in said chamber outside said vessel and having its exit end connected with said liquid-filtering and water-freezing instrumentalities, and having its entrant end adapted to receive refrigerant to be dehydrated; and means for delivering dehydrated refrigerant from said liquid-filtering and water-freezing instrumentalities to the outside of said casing.

10 5. A dehydrator comprising a casing; a vessel within said casing and having a cover; a filter unit held within said vessel; a freezing coil in said vessel, embracing said filter unit; means spacing said coil from said filter unit; a first fitting on said cover with which fitting the entrant end of said coil is joined, the other end of said coil being constructed to deliver liquid into said filter unit; a second fitting on said cover; a duct from 15 said filter unit to said second fitting; a heat interchanger in said casing and comprising an outer coil and an inner coil, means to convey refrigerant from outside said casing to one end of said outer coil, the other end of said outer coil being connected to said first fitting, one end of said inner coil being connected to said second fitting, the other end of said inner coil delivering to the outside of said casing; and means for producing freezing temperatures within said vessel.

20 6. A dehydrator comprising a casing; a vessel within said casing and having a cover; a filter unit held within said vessel; a freezing coil in said vessel; embracing said filter unit; means spacing said coil from said filter unit; a first fitting on said cover with which fitting the entrant end of said coil is joined, the other end of said coil being constructed to deliver liquid into said filter unit; a second fitting on said cover; a duct from 25 said filter unit to said second fitting; a heat interchanger in said casing and comprising an outer coil and an inner coil, means to convey refrigerant from outside said casing to one end of said outer coil, the other end of said outer coil being connected to said first fitting, one end of said inner coil being connected to said second fitting, the other end of said inner coil delivering to the outside of said casing; and means for producing freezing temperatures within said vessel, said last named means including a cup within said vessel, means for conveying a predetermined amount of liquid from said second fitting into said cup, and means to create a partial vacuum in said cup to evaporate refrigerant and thereby lower the temperature in said vessel for purposes described.

25 7. A dehydrator comprising a casing; a vessel within said casing and having a cover; a filter unit held within said vessel; a freezing coil in said vessel, embracing said filter unit; means spacing said coil from said filter unit; a first fitting on said cover with which fitting the entrant end of said coil is joined, the other end of said coil being constructed to deliver liquid into said filter unit; a second fitting on said cover; a duct from 30 said filter unit to said second fitting; a heat interchanger in said casing and comprising an outer coil and an inner coil, means to convey refrigerant from outside said casing to one end of said outer coil, the other end of said outer coil being connected to said first fitting, one end of said inner coil being connected to said second fitting, the other end of said inner coil delivering to the outside of said casing; and means for producing freezing temperatures within said vessel, said last named means including a cup within said vessel, means for conveying a predetermined amount of liquid from said second fitting into said cup, and means to create a partial vacuum in said cup to evaporate refrigerant and thereby lower the temperature in said vessel for purposes described.

interchanger in said casing and comprising an outer coil and an inner coil, means to convey refrigerant from outside said casing to one end of said outer coil, the other end of said outer coil being connected to said first fitting, one end of said inner coil being connected to said second fitting, the other end of said inner coil delivering to the outside of said casing; and means for producing freezing temperatures within said vessel, said last named means including a cup, a regulating valve communicating with said cup and with said second fitting for passing refrigerant into said cup, and a suction duct communicating with the interior of said vessel to effect vaporization of said refrigerant in said cup.

8. A dehydrator comprising a casing; a vessel within said casing and having a cover; a filter unit held within said vessel; a freezing coil in said vessel, embracing said filter unit; means spacing said coil from said filter unit; a first fitting on said cover with which fitting the entrant end of said coil is joined, the other end of said coil being constructed to deliver liquid into said filter unit; a second fitting on said cover; a duct from said filter unit to said second fitting; a heat interchanger in said casing and comprising an outer coil and an inner coil, means to convey refrigerant

erant from outside said casing to one end of said outer coil, the other end of said outer coil being connected to said first fitting, one end of said inner coil being connected to said second fitting, the other end of said inner coil delivering to the outside of said casing; and means for producing freezing temperatures within said vessel, said last named means including a cup, a regulating valve communicating with said cup and with said second fitting for passing refrigerant into said cup, and a suction duct communicating with the interior of said vessel to effect vaporization of said refrigerant in said cup, said regulating valve also having a float-valve controlled outlet.
